(57) **CLAIM**

The ornamental design for a handle, as shown and described.

DESCRIPTION

FIG. 1 is a perspective view of a handle as seen from the front, above and the side;

FIG. 2 is a top plan view thereof;

FIG. 3 is a side elevation view thereof; and,

FIG. 4 is a perspective view as seen from the back, above and the side thereof.

The broken line showing on FIG. 1-4 is for illustrative purposes only and forms no part of the claimed design.
